ROBERT CREUZBAUR, OF NEW YORK, N. Y., ASSIGNOR TO GEORGE H. FRASER AND R. WALTER CREUZBAUR, TRUSTEES, OF SAME PLACE.

MOTOR.

SPECIFICATION forming part of Letters Patent No. 623,137, dated April 18, 1899.

Application filed July 28, 1884. Serial No. 138,987. (No model.)

To all whom it may concern:

Be it known that I, ROBERT CREUZBAUR, of the city of New York, (Brooklyn,) in the county of Kings and State of New York, have 5 invented certain new and useful Improvements in Motors; and I do hereby declare the following to be a full, clear, and exact description of the invention, such as will enable others skilled in the art to which it pertains to 10 make and use the same, reference being had to the accompanying drawings, which form part of this specification.

My invention relates to that class of motors in which a constant mass of elastic fluid is 15 alternately heated and cooled, with consequent increase and decrease of its pressure or volume, or both, during each cycle of the working piston's motion, such different pressures acting constantly upon such piston, 20 without intervening valve, no exhaust of such fluid taking place. The type of such motors is best illustrated by the Stirling air-engine as patented by James Stirling and by Robert Stirling in 1816, 1827, and 1840.

25 The objects of my improvements in such motors are to provide for, first, a reciprocating displacer, which shifts the fluid from the hot to the cold parts of its surrounding fluid-chamber, when such displacer is constructed 30 of two or more hollow sections separated by non-conducting packing, so that the heat in the hot end of the displacer is prevented from wasting into the cold end thereof; sec- 35 ond, a reciprocating displacer shaped as a frustum of a cone or tapered on the outside at both ends, with intermediate parallel sides longer than its stroke, with a corresponding shape of its surrounding fluid-chamber for the purpose of increasing the fluid-chamber 40 surfaces which are laid bare by the end motions of the displacer; third, a recipro- 45 cating tapered displacer which contains the heat storing and transmitting regenerator; fourth, a reciprocating displacer guided ap- proximately midway by a stationary pack- 50 ing-ring, which also causes the fluid to pass through the regenerator located in the dis- placers and prevents its passage along the outside of the displacer; fifth, a pressure- regulator which automatically controls and

maintains the desired mean pressure within the fluid-chamber; sixth, the construction of the main shaft in sections so arranged that the lead of the displacer can be varied in accordance with the more or less rapid action of the 55 elastic fluid used as the expansive medium in the motor; seventh, the combination of a pump with such a motor, so that the pump draws its water through the jacket surrounding the cooling-chamber of the motor; eighth, 60 in a single-acting motor driving a pump, the displacer and the pump-piston so arranged with their connections that they move in unison; ninth, in a single-acting motor the combination, in one vessel, of the heating and 65 cooling chamber on one side of the working piston and the cushion and pump-chamber on the other side of the piston; tenth, in a single-acting motor a cushion-chamber with an automatically-controlled inlet-valve from a 70 source of supply of elastic fluid and an automatically-controlled outlet into the elastic- fluid chamber on the opposite side of the piston for the purpose of controlling the pressure in the motor. I attain these objects by the 75 mechanism illustrated in the accompanying drawings, in which—

Figure 1 is an elevation of the motor, partly in section, with a pump attached. Fig. 2 is a vertical central section, cut in a plane at 80 right angles to Fig. 1, with some of the central parts in elevation. Fig. 3 is a horizontal section on the line A A, Fig. 2. Fig. 4 is a plan of the crank-shaft on a larger scale, partly in section. Fig. 5 is a vertical mid-section 85 looking in the same direction as Fig. 1 and representing part of the apparatus on a larger scale. Fig. 6 is a cross-section, and Fig. 7 a horizontal central section, of the valve z, on the left in Fig. 5, on a larger scale. 90

Referring to the drawings, B is the base or pedestal.

C C' is the fluid-chamber.

I is the displacer.

L is the regenerator, which is arranged 95 within the displacer and moves with it, and N is the working piston.

H is a pump arranged at the top of the motor.

The fluid-chamber C C' is formed of a heated 100

shell or vessel C^3 beneath and a cold shell C^4 above, the two being separated by a non-conducting packing C^2 , of asbestos or other suitable material. The shells C^3 and C^4 are made with double walls forming jackets. The shell C^3 is heated in any suitable way, while the shell C^4 is kept cool by radiation or by passing water through its jacket.

The piston N is fixed to a tubular rod n , which passes out through a stuffing-box at the top of the fluid-chamber and is connected by a forked rod Q to a crank r on the crank-shaft $R R$. The displacer I is fixed to a rod K , which passes out (through the tubular rod n) and is connected through the medium of a cross-piece u , Fig. 1, and rods $t^2 t^2$ to a cross-piece t' , which is connected by pitmen $S' S'$ to cranks $S S$ on the shaft $R R$, these cranks being set in advance of the crank r to give the displacer the requisite "lead" over the piston.

In general the operation of this motor is the same as that of the said Stirling air-engine. The descent of the displacer forces the air, vapor, or other fluid medium in the hot part C of the fluid-chamber to flow up through the regenerator L into the cold part C' of said chamber, whereby the air or vapor is cooled and contracts. During the upstroke of the displacer the air or vapor is forced back through the regenerator, from which it reabsorbs the heat it had previously imparted to it into the hot end of the chamber, whereupon it expands. The expansion of the air or vapor beneath the piston forces it upward, thereby giving an impetus to the crank-shaft and fly-wheel, and the contraction of the air or vapor permits the piston to be returned downward by the momentum of the rotary parts.

I will now proceed to describe in detail the construction of my motor.

The shells C^3 and C^4 are constructed with numerous heat-conducting pegs or cross-bars $C^5 C^5$, crossing the jacket between the inner and the outer shell. These pegs C^5 serve the quadruple purpose of, first, intercepting and dispersing the heat-conveying medium passing through the jacket; second, receiving heat from or conveying heat to such medium; third, conveying heat from one wall to the other wall, thus giving to the inner face of the fluid-chamber greater capacity to give out heat to or absorb heat from such contained fluid, and, fourth, giving to the vessels $C^3 C^4$ greater rigidity and strength. In the heating vessel C^3 these pegs C^5 convey heat to the inner wall, and in the cooling vessel C^4 the pegs carry heat from the inner wall to the outer wall.

The heat pegs or lugs need not necessarily extend into or to the outer walls of the respective jackets, being mere projections from the inner walls and so constructed that they will fulfil the first and second of the conditions above stated.

The heating vessel C^3 may be heated in various ways, either by a grate-fire under it, or

by the heat conveyed from such fire into the vessel's jacket, or by a gas or oil flame under it.

The drawings represent the heating-shell C^3 as being heated by gas-jets from a circular burner D .

D' is fire-brick surrounding the gas or oil flame, formed with staggered or overlapping top openings, so that the heat and flames are reverberated, thus producing more perfect combustion.

E is a plate supporting the fire-bricks with openings e to admit air. The quantity of air admitted is regulated by a register plate or disk e' , having corresponding air-openings, which plate is revolved in order to open or close the openings, as desired. The spent fire-gases either escape at openings $F F$, Fig. 85 1, or collect in the circular channel f , Fig. 5, and are carried off by a chimney f' .

The jacket of the cooling-shell C^4 has one or more inlets $G G'$, Fig. 1, and one or more outlets $g' g'$, through which when air is the elastic medium used in the motor water flows, entering at G and passing out at g on its way to the pump H , or when less heat is to be thus extracted the water may enter at G and flow out at G' , or it may enter at g and flow out at g' . These ports may be duplicated on opposite sides, making four ports $G G'$ below and four ports $g' g'$ above.

When steam is used as the elastic medium in the motor, no water is passed through the jacket of cooling-shell C^4 , as the steam contracts by the loss of the heat which is transformed into the work it does, as well as by the loss of the heat absorbed by shell C^4 . The better to control the contraction of the steam, so as to avoid undue resistance while the steam is being returned to its smaller volume by the return or down stroke of the working piston N , the ports $G G' g' g'$ may be more or less opened, so as to cause a current of air to flow through the jacket of shell C^4 .

The displacer I is divided transversely into two or more sections, which are insulated from each other in order to prevent or obstruct the passage of heat from one to another, thereby reducing to the utmost the waste which ensues from the transmission of heat from the hot to the cold end of the displacer. I construct the displacer of three sections $i, i',$ and i'' , the former being the hot section, the latter being the cold section, and the intermediate one the neutral section. The hot section is always in the heating vessel C^3 and the cold section is always in the cooling vessel C^4 , but the neutral section is partly in one vessel and partly in the other, being shifted back or forth as the displacer reciprocates. Between the sections are layers of non-conducting packing $i^3 i^3$ of any material which is a poor conductor of heat, asbestos being preferred. The three sections are made as hollow shells, the air confined in them contributing to render them non-conductive of heat, or they may be filled with

non-conducting material. I make the packing i^3 to extend across the hollow spaces, whereby the confined air is divided into three chambers, whereby any circulation of the air from a hot to a cool portion of the displacer is prevented.

I am aware that a piston-shaped displacer has been made of two hollow shells packed with asbestos and separated by metallic packing-rings and inclosing a single air-space between the two shells. In this construction, however, the two shells are in metallic, and consequently conductive, connection with each other, so that a considerable leakage of heat must necessarily occur from the hot to the cold shell. To reduce this, the displacer referred to is formed with a water-jacket on its cold side in order that the heat thus conducted to the cold side may be taken up by the water.

My invention renders the water-jacket unnecessary, thereby dispensing with the telescopic pipes, packings, and pump which are necessary to conduct water to and from a moving piston, and consequently greatly simplifying and cheapening the apparatus, while maintaining the higher efficiency due to keeping the displacer hot on its one side and cold on its other side.

The three sections of the displacer are made of annular form, each of the shells having a cylindrical opening formed through its center. Inside of these openings is placed a tube i^4 , which serves to aline the sections and prevent their lateral displacement. The sections are held together by means of the rod K, which has a shoulder formed on it where it enters the top of the displacer, and its lower end screws into a socket formed at the bottom of the section i , as shown in Fig. 5.

The displacer I is guided on the top by its rod K and midway by a packing-ring M, which is split or otherwise grooved, so that condensed steam can trickle through or past it into the hot chamber C. The drawings show the ring M to be axially stationary, whereby the cheaper finish of the part of the displacer sliding upon the ring takes the place of the more costly corresponding finish of the cool section of the shell, which would be necessary if the ring were incorporated in the cool section of the displacer, as in usual piston-packing; but it is evident that the ring may be applied in either way. The displacer is to have a clearance of from one sixty-fourth to one thirty-second of an inch all around, except where its middle section i^2 is guided by the said packing-ring M, so that the pressure upon the displacer is balanced all around it. The displacer may be formed of a cool section and a hot section only, omitting a neutral separate intermediate part i' , which in such case is incorporated with the cool part i^2 , so that the parallel part working in contact with the packing-ring will remain at a low temperature.

The regenerator is formed thus: The space

L between the rod K and the tube i^4 is filled up with thin metal strips separated by their thickened edges and by longitudinal ridges formed upon them, so that about half such space is filled up with such metal strips throughout the tube i^4 , leaving the spaces between the strips about one thirty-second of an inch for the passage of the elastic fluid through the displacer, the upper end of section i^2 and the lower end of section i being formed with ports, as indicated by the arrows. These ports may be formed in loose pieces, held in place by rod K. The motor may be used without a regenerator, particularly when steam or other vapor is the medium applied. In such case the regenerator-space and the guide and packing-ring M may be omitted and the displacer guided at the bottom, as shown in my Patent No. 210,840, of date December 17, 1878. The vapor will then flow around the exterior of the displacer in passing from one chamber C C' to the other.

The displacer is formed with its ends tapered, and the chambers C C' are correspondingly shaped. When the displacer is at its extreme upstroke, as shown in Figs. 1 and 5, its upper section i^2 conforms to and fills the cold chamber C', (up as far as the extreme downstroke of the piston,) leaving around it only the slight clearance above mentioned of from one sixty-fourth to one thirty-second of an inch. Thus the fluid is as far as possible displaced from the cold chamber, while at the same time the hot chamber beneath is expanded to its utmost capacity, there being a wide space all around between the section i of the displacer and the wall of the chamber, as shown. When the displacer is at extreme downstroke, its lower section completely fills the hot chamber, (excepting only the clearance before specified,) while between its upper section and the wall of the cold chamber there is a considerable space. Thus in each of the chambers C C' the space or clearance around the displacer widens and narrows as the displacer reciprocates, so that the fluid is forced to circulate thoroughly over the entire surface of both chambers. This construction constitutes an important feature of my invention, resulting in a degree of efficiency in the heating and cooling of the fluid that is unattainable in a motor having a cylindrical displacer working in a cylindrical chamber, since in such motors the clearance around the displacer being of unvarying width becomes filled with fluid, which remains comparatively quiescent when fitted with a packing-ring and a central regenerator, and hence the surface covered by such fluid becomes comparatively inert or ineffective. Furthermore, by my construction the displacer may have a much shorter stroke, since at each reciprocation a heating or cooling surface several times the length of the stroke is laid bare.

The tubular rod n of the working piston N passes out through a stuffing-box n', Fig. 5,

and is firmly attached by gland n^2 to an outer sleeve P, which carries the wrist-pins $p' p'$ and serves as a cross-head by sliding upon the stuffing-box casing n^3 , thereby greatly 5 reducing the required space between the stuffing-box and the crank-shaft.

The forked connecting-rod Q is attached to the wrist-pins $p' p'$ and to the crank r in the usual way, thus giving motion to the crank-shaft R R' R and to the fly and band wheels attached thereto.

The rod K, which carries the displacer I, is packed within the working piston by a packing K', retained by gland K ^{2} , and by a packing under the upper gland n^2 above named. 15 The space between these two packings may be filled with glycerin or similar viscid and suitable fluid.

The displacer receives motion as follows: 20 Duplicate eccentric wrist pins or cranks S S on crank-shaft sections R R give motion through connecting-rods S' S' to cross-bar T, guided by guides t t. This bar T has two arms t' t', Figs. 1 and 3, extending at right 25 angles, forming a cross. From the ends of these arms t' t' rods t ^{2} t ^{2} , Fig. 1, extend down and take hold of bar U, Figs. 1 and 2, to which the displacer-rod K is centrally attached. When a pump H is used, the piston-rod h ^{2} of its piston h ^{2} is centrally attached to the cross-head T t' t, so that the pump-piston h ^{2} and the displacer I move in unison, the downstroke of the displacer being the working stroke of the single-acting piston h ^{2} . The 30 suction-valve is w ^{2} , w ^{2} is the delivery-valve, Y Y the suction air-chamber, and Y' the delivery air-chamber. When the motor is used with air, the suction of the pump is connected to the jacket or shell C ^{4} at g or g', so that the 35 water which enters the pump is drawn through the cooling-jacket. Heretofore water has been forced through the cooling-jacket after leaving the pump, thus rendering its discharge circuitous and necessitating that the shell 40 shall be made enough stronger to enable it to withstand the added pressure of the water. With my arrangement the water in the cooling-jacket is at less than atmospheric pressure. When no pump is used, the pillow-block frames V V are extended up high enough 45 to support the guides t t.

The displacer I has more or less "lead," about seventy degrees when air is used, and less when steam is used, varying also with 50 the speed at which the engine is to be run. To illustrate, when the piston has completed its working stroke, with its crank-pin on the upper dead-point, as in Fig. 2, the displacer has performed part of its downstroke to the 55 extent of about seventy degrees between their respective crank-pins. This gives the elastic fluid time to contract by the loss of heat while the piston crank-pin is passing its dead-point and allows the piston to return with greatly- 60 reduced opposing pressure. To be able to regulate this lead according to the requirements, the crank-shaft is made in three sec-

tions—the middle section R', Fig. 4, which includes the central crank r and the two bearings 8 8, connected by disks r' r', and the two 70 end sections R R, each comprising a wrist pin or crank S and a shaft extension carrying the fly-wheel, joined by disks r ^{2} r ^{2} . These sections R R' R are joined together by disks r ^{3} r ^{4} , bolted together, as shown, a central stud on disk r ^{3} entering a corresponding hole in disk r ^{4} . The bolt-holes on one disk are differentially located from those in the other disk, so that only two opposite bolt-holes will match, it being necessary to revolve the disks 80 on each other to get two other bolt-holes to match, thus giving the means for reducing or increasing the lead of the displacer, or one or both disks r ^{3} r ^{4} may be suitably slotted to admit of their being rotated in reverse directions when their clamping-bolt is slackened. 85 Any suitable adjusting device may be applied to these disks, so that one may be turned relatively to the other within the limits demanded in practice. In fact, any construction by 90 which the cranks or wrist-pins S S may be adjusted relatively to the crank r in order to vary the lead of the displacer is within the scope of my invention.

I will now proceed to describe the method 95 whereby the gaseous pressure within the motor is regulated. Above the piston N is a cushion-chamber W of a maximum capacity of about 1.25 times the piston displacement, more or less, its capacity depending upon the 100 piston-pressure desired. To the cushion-chamber W is connected a regulator 2, (shown in Fig. 5,) which is provided with a valve 3, opening toward the chamber W. When air is the fluid used in the motor, the regulator 105 2 may be omitted, the valve 3 in such case opening directly from the atmosphere, or the regulator may be used by providing an air-opening into it—as, for instance, by removing the closed guide plug or cap 4 shown 110 and substituting for it an open guide-plug—through which the atmosphere has free access. From the cushion-chamber W a passage x extends around the piston and opens into the fluid-chamber at a point x', Fig. 5, 115 beneath the lowest position of the piston. In Fig. 5 is shown the preferred construction, wherein an inlet-valve Z is provided, acting to close the passage to any pressure tending to escape from the chamber C', but to freely 120 open to admit a flow into said chamber. The air confined in the cushion-chamber W is alternately compressed and expanded by the movements of the piston. If when it is expanded to its utmost at the extreme downstroke of the piston its pressure falls below that of the atmosphere, air is drawn in through valve 3 to equalize the pressure. Upon the upstroke 125 of the piston the confined air is compressed. At about the same time the pressure beneath 130 the piston is at its minimum, having been reduced partly by reason of the expansion due to the upward movement of the piston, partly by its loss of heat converted into work done

in driving the piston upward, and partly by the loss of heat abstracted by the cold casing C'. If at the instant when the pressure beneath the piston reaches its minimum it is enough less than the pressure of the compressed air above the piston to overcome the tension of the spring holding the valve Z closed some of the fluid will pass through the valve into the chamber beneath the piston. Thus the minimum pressure in chamber W is regulated by that of the external atmosphere, while the minimum pressure under the piston is regulated by the maximum pressure in chamber W.

To illustrate, let us assume that the capacity of the cushion-space is such that the upstroke of the piston compresses the confined air from atmospheric pressure up to twenty-seven pounds per square inch. If at the same time the minimum pressure beneath the piston falls below twenty-seven pounds, enough air will tend to pass from the cushion-chamber through the valve Z to equalize at that instant the pressures above and below the piston, and when the piston reaches its lowest position the air above it will, owing to the portion it has lost, become expanded to less than atmospheric pressure, and will consequently replenish itself by drawing in a fresh quantity of air from outside. In this illustration I have ignored the slight effect that is due to the pressure of the springs that seat the valves 3 and Z. It is to be understood that these pressure-valves are in action only at the starting of the engine for pumping up the requisite pressure and subsequently to replace any air that may escape by leakage or absorption. Under the normal operation of the motor they should remain inactive. The working pressure of the motor can therefore be raised or lowered independently of the temperature of the furnace-fire, the latter remaining constant, by diminishing or increasing the dead-space in chamber W and the spaces connected therewith, which may be done in various ways, adjustably or static.

Inasmuch as air is more effective when saturated with vapor, it is advantageous to employ the regulator-chamber 2, even when operating the motor as an air-engine, using it as an evaporator for moistening the entering air. For this purpose it is filled with water, and in order to vaporize this water the flue f' for the escaping fire-gases is conducted to and around the regulator-chamber, as shown in Fig. 5.

The valve Z may be constructed in various ways. The preferred construction is that shown in Fig. 5 and on a larger scale in Figs. 6 and 7. To prevent the lodging of water in the valve-chamber z', Fig. 7, this chamber is made to drain by locating the spring which closes the valve inside the hollow valve-stem, which is grooved lengthwise at the bottom, so as to drain the condensed water downward.

The spring at one end abuts upon a transverse pin z², which passes through opposite

slots in the valve-stem, as shown, and pierces the valve-casing z³, and at the other end the spring abuts against a plug z⁴, screwed into the end of the hollow valve-stem.

In cheaper engines it may be desirable to avoid the expense of the valve Z, in which case the construction of channel x x' shown in Fig. 2 may be used. The channel x is here a valveless port, extending from the cushion-chamber downward and opening into the chamber C' at x', just beneath the piston when the latter is at its extreme upstroke. Thus at this instant communication is established between the opposite sides of the piston. Immediately the piston commences its descent it covers and shuts off the opening x'.

When steam is used as the elastic fluid, the atmosphere is excluded from the reservoir 2, and a valve 5 is attached to the top of it, opening into a condensing-chamber 6, this valve being loaded by a spring or by weights 7 7, so as to open at any pressure above that to be maintained in regulator-chamber 2. Thus when the valve 5 is opened by overpressure under it the vapor escaping through the valve is condensed in chamber 6 and returns into chamber 2 as water when the valve is again opened by overpressure. This valve 5 and condensing-chamber 6 would be unnecessary if a constant pressure could be otherwise maintained in regulator 2, and they are unnecessary when a variation of pressure is of no serious consequence, as in pumping water or propelling a boat. In such cases, although steam be used as the elastic medium in the motor, the valve 5 and condenser 6 are omitted. The reservoir 2 is preferably heated in every case. The valve 5 and the spring or weights 7 7 may be applied without the condensing-chamber 6, the surplus vapors in that case escaping into the atmosphere or otherwise.

When the motor is double-acting—that is, without cushion-chamber W and in place thereof another heating and cooling chamber C' and displacer I are acting upon the piston on that side, as shown in Letters Patent of the United States No. 210,840, issued to me December 17, 1878—a regulator-reservoir 2, with its attachments, is affixed to each fluid-chamber on opposite sides of the piston.

When steam is used with a single-acting motor, the reservoir 2 might also be applied to the active side of the piston and the pressure in the cushion-chamber W allowed to regulate itself.

Instead of a check-valve 3 between the reservoir 2 and the motor-fluid chamber a slide or other valve opening periodically at a fixed period of the motor's cycle of motion might be used, the pressure in reservoir 2 being regulated accordingly; but the simplest method of regulating the pressure in the fluid-chambers of the motor on either side of the piston is by the use of a check-valve 3, as shown and described.

For controlling the speed of the motor I

provide means for establishing communication between the opposite sides of the piston at will, thereby equalizing more or less the opposite pressures, and consequently depriving the piston of more or less of its power and reducing its speed. I employ for this purpose a passage or by-pass leading from one side of the piston to the other and a by-pass valve in said passage, which is normally closed, but which is adapted to be opened from the exterior either by hand or by the action of an automatic governor. In the construction of engine shown in the drawings the valve Z is utilized as this speed-regulating valve in addition to its function as a pressure-regulating valve. For this purpose a spindle 12, Figs. 5, 6, and 7, extends through a stuffing-box 13 into the chamber z' of the valve Z, where the spindle is squared, and carries a toe 14, by which through the turning of the spindle 12 the valve Z is opened, and more or less of an equilibrium is established on opposite sides of the piston. The toe 14 when not in action is returned into its normal position of rest, so as not to impede the free automatic action of valve Z when regulating the pressure of the fluid in the motor. On the outside the stem 12 is connected in the usual way to a hand-lever, if the motor is to be controlled by hand, or to a governor, if it is to be regulated automatically. While the valve Z is thus opened to check the speed of the motor, the mean pressure in cushion-chamber W rises above its normal pressure for the best economy and power of the motor; but as soon as valve Z is closed and ceases to be active as a speed-governing valve it immediately comes into action as the pressure-regulating valve, returning to the main fluid-chamber under the piston the fluid delivered into the chamber W to check the speed of the motor. In large motors a special balanced speed-governing valve is used, located in such a channel connecting the fluid-chambers on opposite sides of the working piston.

By withdrawing the plug-screw 10 at the bottom of chamber C the water can be withdrawn, so as to remove abrasions from the metal or other impurities apt to be present in a new machine.

The operation of the motor may now be described in detail. With air as the elastic medium, heat having been applied to the motor, a few turns of the fly-wheel by hand will pump in air under the piston until the pressure there is sufficient to set the motor in motion. The delivery of more air under the piston will then continue until the minimum pressure under the piston has reached the maximum pressure over the piston and the minimum pressure over the piston has reached the pressure of the atmosphere. The displacer being near its upper dead-point, as in Figs. 1 and 5, just commencing to move downward, the piston is moving upward, impelled by the increased pressure in the fluid, caused

by its full contact in bulk with the hot surfaces of heating-shell C³. In moving downward the displacer forces the air under it through the regenerator in L, where it lodges most of the heat not absorbed by the work done. More heat is absorbed by the cold surfaces of the cooling-shell C⁴, through the jacket of which a current of water is caused to flow, as above described. The pressure under the piston after the latter has reached its upper dead-point is thus greatly reduced and the piston is enabled to make its return stroke, impelled by the fly-wheel, with far less expenditure of force than that exerted upon the piston by the expanding fluid during its upward or working stroke. After the piston has made over half its return or downward stroke the displacer begins to move upward, forcing the cold air above it to pass through the regenerator, picking up the heat it lodged there on its upward course, and filling the space under the displacer, where it again comes in contact in bulk with the hot walls of the shell C³ and is exposed to the radiation of heat therefrom. Its increase of pressure by the higher temperature thus imparted to it again causes the piston to move upward after completing its downward stroke, and so on. When steam is used instead of air, sufficient water is introduced into the elastic-fluid chamber through any convenient opening—say, at 9, Fig. 2—to fill it with saturated steam at maximum pressure and minimum volume. The piston being in its uppermost position, the water will run down through channel x x' and through the split or grooved packing-ring M down into the hot chamber C, where it is formed into steam. After that no more water is introduced except occasionally into the regulator 2 to make up for leakage, as described.

I claim as my invention the following-defined novel features, substantially as hereinbefore specified, namely:

1. A displacer tapered exteriorly at both ends to form frustums of cones, combined with a fluid-chamber having correspondingly-tapered ends and an intermediate parallel portion of length at least equal to the stroke of the displacer.

2. A heating and cooling chamber tapered at both ends, combined with a displacer having correspondingly-tapered ends, and a parallel middle portion of length equal to its stroke, and a packing-ring mounted in the chamber and acting on the parallel portion of the displacer.

3. In a non-exhaust motor, a hollow displacer shaped at both ends as a frustum of a cone or tapered upon the outside, and having parallel sides between the coned ends, longer than its stroke.

4. A reciprocating displacer constructed in sections, each section being a hollow shell of metal, and the sections being isolated from one another by an intervening transverse layer of non-metallic packing of low conduc-

- tion of heat, extending across the hollow spaces and dividing them into separate chambers, substantially as specified.
5. A reciprocating displacer constructed of three sections, namely, a hot section at one end, a cool section at the opposite end, and a neutral section between them, with isolating layers of non-conducting material interposed between the sections to prevent conduction of heat from one to another.
6. The combination with a fluid-chamber constructed of a heating-shell at one end, and a cooling-shell at the other, and having a stationary packing-ring, of a reciprocating displacer in said chamber constructed in sections, with its middle portion, which works in said packing-ring, cylindrical and with its end portion in said heating-section isolated from said middle portion by a non-conducting packing, substantially as specified.
7. The combination with a fluid-chamber constructed of a heating-shell at one end, and a cooling-shell at the other, and having a stationary packing-ring, of a reciprocating displacer in said chamber constructed in three sections, isolated from one another, namely, a hot section located in the heating-shell, a cool section located in the cooling-shell, and a cylindrical neutral section between them which in the reciprocation of the displacer moves in said packing-ring, substantially as set forth.
8. The combination with a fluid-chamber constructed of a heating-shell at one end, and a cooling-shell at the other, of a reciprocating displacer in said chamber, a heat-regenerator located in a central tube formed in the displacer and moving therewith, and a packing-ring between the shell and the displacer, adapted to prevent the passage of gases around the displacer, and thereby to force them through the regenerator, substantially as specified.
9. The combination of a displacer constructed of sections laterally aligned and confined by a tube passing centrally through the sections, with a regenerator borne by and moving with the displacer, and located within said tube, substantially as specified.
10. The combination of a non-exhaust motor having heating and cooling jackets, with a water-pump operated thereby and having its suction connected to the cooling-jacket of said motor, the water being caused to enter the jacket by the motion of the pump, whereby it draws its supply through said cooling-jacket at a pressure therein due to its head or pressure, and to the suction of the pump, and delivers it at a higher level, substantially as specified.
11. The combination of a displacer, a working piston, and a crank-shaft constructed with cranks connected respectively to said working piston, and to said displacer, and adjustable relatively, in order to vary the lead of the displacer, substantially as specified.
12. The combination of a displacer, a work-
- ing piston, their respective connecting-rods and a crank-shaft, the latter constructed in sections having abutting disks by which said sections are connected together, whereby they may be angularly adjusted in order to vary the lead of the displacer over the piston, substantially as specified.
13. In a single-acting motor, the combination with the working piston of a heating and cooling chamber on one side of such piston, and a cushioning and pumping chamber on the other side thereof, constructed to normally confine an unvarying charge of fluid which is compressed during the power-stroke of the piston and re-expands during the return stroke, substantially as specified.
14. In a single-acting motor, the combination with the working piston of a heating and cooling chamber on one side of said piston, a cushion-chamber on the other side of said piston, and an inlet-valve opening into said cushion-chamber, substantially as specified.
15. In a single-acting motor, the combination with the working piston of a heating and cooling chamber on one side thereof, a cushion-chamber on the opposite side thereof, and a communicating passage extending from the cushion-chamber and opening to the opposite side of the piston when the latter is at the end of its power-stroke, substantially as specified.
16. In a single-acting motor, the combination of the power-piston, a cushion-chamber on one side thereof, a heating and cooling chamber on the opposite side thereof, an equilibrium-channel leading from the cushion-chamber to the heating and cooling chamber, provided with a check-valve opening toward the latter chamber, substantially as set forth.
17. In a single-acting motor, the combination of the working piston, a heating and cooling chamber on one side thereof, a cushion-chamber on the other side thereof, an inlet-valve opening into said cushion-chamber, a passage extending from the cushion-chamber to the heating and cooling chamber, and a valve in said passage opening toward the latter chamber, substantially as specified.
18. In a single-acting motor, the combination of the working piston, a heating and cooling chamber communicating with one side thereof, a cushion-chamber on the other side thereof, a passage connecting said chambers, a by-pass valve in said passage, and means for opening said valve from the exterior to permit a free flow of fluid around the piston and thereby to control the speed of the motor, substantially as set forth.
19. In a single-acting motor, the combination of the working piston, a passage connecting the chambers on opposite sides of the piston, a check-valve in said passage opening into the active-fluid chamber, and means for opening said valve from the exterior, in order to permit a flow of gases from the active-fluid chamber, and thereby to control the speed of the motor, substantially as specified, whereby when such means are in disuse the

- function of said valve as a check-valve is not impaired.
20. In a non-exhaust motor, an auxiliary fluid-evaporating chamber and means for heating it, combined with the working chamber of the motor, and a valved passage adapted to admit the vapor generated in said evaporating-chamber into said working chamber.
21. In a non-exhaust motor, the combination of an auxiliary fluid-evaporating chamber and means for heating it, the working chamber of the motor, a valved passage adapted to admit the vapor from said evaporating-chamber into said working chamber, and a passage closed by a loaded valve adapted to allow a surplus of vapor to escape into the atmosphere or a condenser.
22. In a non-exhaust motor, comprising a piston, its working chamber, and a combustion-chamber, the combination therewith of an auxiliary evaporating-chamber, a valved passage for admitting the vapor generated in said evaporating-chamber into said working chamber, and means for heating said evaporating-chamber consisting of a flue conducting the waste fire-gases from said combustion-chamber into contact with said evaporating-chamber.
23. In a non-exhaust motor, the combination with an auxiliary fluid-evaporating chamber and means for heating it, the working chamber of the motor, a valved passage adapted to admit the resulting vapor from said evaporating-chamber into said working chamber, and a condensing-tube, together with a passage from said evaporating-chamber into said condensing-tube, and a weighted valve normally closed, adapted to control said passage into said condensing-tube.
24. In a non-exhaust motor, in combination with the heating and cooling shells containing working fluid, of means adapted to increase the range of the alternating temperature of such working fluid, consisting substantially of the connected working-fluid heating-chamber C, and cooling-chamber C' formed by shells C³ and C⁴, in combination with pegs C⁵ integrally connecting either or both of said shells C³, C⁴, with their respective outer shells forming jackets of different temperatures around said connected working-fluid chambers C, C', substantially as shown and described.
25. A displacer formed of three hollow sections transversely divided, one end section thereof being tapered as the frustum of a cone, and arranged to reciprocate only within the cooling shell or chamber, the middle section thereof formed cylindrical, and arranged to reciprocate alternately into the cooling-chamber and into the heating-chamber, and the other end section thereof also tapered as the frustum of a cone, and arranged to reciprocate only within the heating shell or chamber, together with heat and fluid intercepting packing between said sections.
26. A displacer consisting of three hollow sections, separated by heat and current intercepting packing, the two end sections arranged to reciprocate respectively in the cold and in the hot shells, and the middle section arranged to alternately enter both the cold and the hot shell.
27. A displacer consisting of three hollow sections separated by heat and current intercepting packing, the two end sections arranged to reciprocate respectively in the cold and hot shells, and the middle section arranged to alternately enter both the cold and the hot shell, in combination with a fluid-channel through the displacer.
28. In a non-exhaust motor, the combination with the heating-shell of the heating and cooling chamber, the furnace, and its flame-space, of fixed fire-brick intervening between the fuel and flame space, and the heating-shell, whereby the burning out of the latter is prevented or retarded and the fuel combustion is improved.
29. In a non-exhaust motor, the combination with the heating-shell of the heating and cooling chamber, and the furnace, of fire-brick with staggered or overlapping openings through the same, whereby the combustion is improved and the heating-shell protected.
30. The combination with a non-exhaust motor, of a gas-furnace having fire-brick intervening between the flame-space and the heating-shell of the motor, and adjustable air-inlets into the flame-space, whereby complete combustion may be attained, and the oxidation and destruction of the heating-shell prevented or retarded.
31. In a non-exhaust motor, the combination with the heating and cooling chamber, and a jacket upon its cooling-section, together with a cooling fluid adapted to pass through such jacket, of interchangeable inlets and outlets upon such jacket, whereby the temperature within the same may be regulated.
32. In a non-exhaust motor, the combination of the heating and cooling chamber and a displacer, both having tapered ends, whereby the heating or cooling surface of said chamber laid bare by a reciprocation of the displacer is largely in excess of the stroke of the displacer, a regenerator through which the inclosed fluid must flow in passing between the hot and cool part of said chamber, and a packing-ring adapted to force the fluid to pass through said regenerator.
33. The combination with a non-exhaust motor, comprising a heating and cooling chamber and a displacer, and a working piston and cylinder, of means for determining the maximum working pressure of the non-exhaust fluid, consisting of a pumping cylinder and piston having a given clearance, an inlet-valve from a supply of the working fluid opening into said pumping-cylinder, and a valve-controlled passage from said cylinder into the heating and cooling chamber, whereby the

clearance between said pumping-piston and its cylinder determines the working pressure in the motor.

34. In a non-exhaust reciprocating motor, 5 the connection between the power-piston and the crank-shaft substantially as shown and described, to wit, the power-piston, its piston-rod, the piston-rod stuffing-box, a sleeve around such stuffing-box, formed with two opposite wrist-pins, and adapted to slide upon 10 the said stuffing-box, a fixed connection be-

tween such sleeve and the piston-rod at their upper ends, and a forked connecting-rod coupled to said wrist-pins at one end, and to the crank-pin upon the crank-shaft at the other 15 end, whereby the dimensions of the motor, in the directions of its reciprocations, are reduced.
